UNITED STATES PATENT OFFICE.

RALPH S. JENNINGS, OF BALTIMORE, MARYLAND.

REFRIGERATOR.

SPECIFICATION forming part of Letters Patent No. 268,493, dated December 5, 1882.

Application filed September 25, 1882. (No model.)

To all whom it may concern:

Be it known that I, RALPH S. JENNINGS, of the city and county of Baltimore, of the State of Maryland, have invented a new and useful Improvement in Refrigerators; and I do hereby declare the same to be described in the following specification and represented in the accompanying drawings, of which—

Figure 1 is a front elevation, Fig. 2 a rear view, and Fig. 3 a horizontal section, of the series of shelves and their surrounding cooling-case appertaining to my invention. Fig. 4 is a transverse and vertical section of the refrigerator.

15 The nature of my invention is defined in the claims hereinafter.

In this refrigerator each of the shelves is hollow and contains a horizontal partition, which is disposed midway between the top and bottom of the space in the shelf, but does not extend entirely to the front of such space. The portion of the space which is immediately over the partition opens into a flat tube or conduit that leads therefrom nearly up to the top of the chamber in which the shelves are placed. The portion of the space which is below the partition opens directly into a chamber in rear of it, within which is a perforated platform or grid for sustaining ice.

30 In the drawings, the outer case of the refrigerator is shown at A as having openings a in its front provided with doors b. In rear of these openings, and between such and the cold-air-chamber c, provided, as described, with the ice-sustaining grid d, is the series of hollow shelves e, within each of which is a partition, f. The pipes that lead upward from the spaces over the partitions are shown at g in Figs. 2, 3, and 4. Furthermore, the series 40 of shelves has extending up through it at its middle a hollow partition, h, which opens into a hollow casing, i, surrounding the series of shelves, except at the front and rear thereof. The hollow casing, as well as the vertical hollow divisional and shelf-supporting partition, freely communicates with the spaces within the hollow shelves, in order that cool air received within the shelves may circulate 45 within the casing and hollow partition to aid 50 in cooling the spaces between the shelves.

There is to be in the wooden casing, at one end thereof, an opening provided with a door, such opening being to communicate with the space directly over the grid and to enable ice to be supplied thereto as occasion may require. The shelves, their partitions and surrounding hollow casing, I usually construct of sheet metal and the surrounding case of wood.

55 In the operation of this refrigerator the cool air, descending within the chamber in rear of the shelves, flows into each shelf and around its partition and escapes by means of the pipe leading upward from each partition nearly to the top of such chamber. Becoming raised in temperature in its course, the air flows over and upon the ice, and by contact therewith falls in temperature, and again descends within the chamber to again enter and pass through the shelves. The lowermost shelf of the series is at or just above the bottom of the surrounding wooden case, such shelf constituting the bottom of the cooling space or spaces immediately over it.

60 By this construction of the refrigerator it becomes divided into a series of cooling apartments or spaces between the shelves, which, if desirable, may be provided with separate doors, in order that when access may be desirable to any one of such apartments it may be had without having to open any of the others. These cooling-apartments are for reception of edible articles or vessels containing liquids to be cooled or preserved from decay or decomposition.

65 I claim, in the refrigerator—

1. The series of hollow shelves provided with partitions and escape-pipes, as described, in combination with an ice-holding or refrigerating chamber arranged in rear of and to communicate with them, all being substantially as set forth.

70 2. The combination of the hollow casing surrounding the hollow shelves, as set forth, with them, their horizontal partitions, escape-pipes, and refrigerating-chamber, arranged substantially as shown and described.

75 3. The combination of the vertical hollow partition extending upward through the hollow shelves, with them, their horizontal partitions, escape-pipes, and refrigerating-cham- 80

ber, all being arranged and adapted substantially as set forth.

4. The combination of the hollow casing surrounding the hollow shelves, as set forth, and the hollow partition extending upward through them, with them, their horizontal partitions and escape-pipes, and the refrigerating-cham-

ber arranged in rear of them, all being substantially as shown and described.

RALPH S. JENNINGS.
